DISTRIBUTING SYSTEM FOR ELECTRIC RAILWAYS.

1,295,933.

Specification of Letters Patent.

Patented Mar. 4, 1919.

Application filed March 8, 1917. Serial No. 153,312.

To all whom it may concern:

Be it known that I, CHARLES F. SCOTT, a citizen of the United States, and a resident of New Haven, in the county of New Haven and State of Connecticut, have invented a new and useful Improvement in Distributing Systems for Electric Railways, of which the following is a specification.

My invention relates to electrical distributing systems and particularly to electrical railway systems that employ alternating currents for propulsion purposes and embody means for minimizing inductive disturbances that are likely to arise from the flow of the power currents.

More particularly, my invention relates to electric railway systems of the above-indicated character in which the several spaced sub-stations comprise transformer windings by means of which the power currents are supplied to the railway sections immediately adjacent to the sub-stations. The windings of these transformers are so related that the inductive effects arising from the currents supplied to the load are minimized or substantially neutralized by the inductive effects arising from the return currents. Moreover, the transformer windings embodied in each sub-station are so combined and interconnected that they may be wound on a common transformer core.

Intelligence-transmission circuits, such as telephone and telegraph circuits, are frequently disposed adjacent to an electric railway and are, therefore, subject to inductive disturbances arising from the flow of the propulsion currents in the railway circuit. To minimize the inductive disturbances that are frequently impressed upon adjacent intelligence-transmission circuits and seriously interfere with their satisfactory operation, many systems have been heretofore proposed a particular one upon which my present invention is an improvement being disclosed in a copending patent application of A. W. Copley and Chas. LeG. Fortescue, Serial No. 66,733, filed December 14, 1915, and assigned to the Westinghouse Electric and Manufacturing Company.

In the aforementioned patent application, the system shown contemplates the use of series transformers for inductively interlinking the trolley and feeder conductors of the railway system with each other. It is intended that the feeder conductor and the

trolley conductor shall be so positioned with respect to an adjacent intelligence-transmission circuit which it is desired to protect against inductive disturbances, that the electromotive forces induced therein by the trolley and feeder currents, shall be substantially completely neutralized. Although the trolley and feeder conductors are inductively interlinked, the propulsion currents must, of necessity, flow in certain portions of the track circuit which comprise the rail sections upon which the active loads obtain.

In order to substantially neutralize the effects of the propulsion currents flowing in the track sections of the system in which no loads obtain, the track circuit is interconnected, through auto-transformers, with the trolley and feeder conductors in such manner as to conduct the propulsion currents from the track circuit except in those sections in which power is required by the loads. At the same time, neutralizing currents are induced to flow in the local circuits established through the load and the transformers at the ends of the section of the track circuit in which the load is temporarily situated. These currents are effective in neutralizing or minimizing, to a very large extent, any disturbances that may result from the propulsion currents in the track sections in which the active loads obtain.

An object of my present invention is to provide a distributing system that is similar to the one disclosed in the above-indicated copending patent application but which comprises inductively related transformer windings that are so interconnected and interrelated with one another that they may be combined in a single magnetic structure. Since these transformers are to be placed at intervals in the railway circuit, it is desirable to make them as inexpensive and simple in construction as possible which is best obtained by providing a unitary structure that will occupy only a small amount of installation space, as well as, reduce the first cost of the installation.

For a better understanding of the nature and scope of my invention, reference may be had to the following description and the accompanying drawing in which Figure 1 is a diagrammatic view of an alternating-current railway system embodying a form of my invention; Fig. 2 is a simplified diagram illustrating the system shown in Fig. 110

1, and Fig. 3 is a diagrammatic view of a single transformer in which all of the power-transformer windings of Fig. 1 are incorporated, thus providing a unitary 5 structure.

The system herein described has for its further object the division of the track and feeder circuits into sections through the use of auto-transformers. The voltage between 10 the feeder and trolley is, for example, 22,000 volts and it is desired to operate the vehicle traversing said system from a 11,000 - volt source of supply. In order to confine the currents flowing in the track circuit to the 15 section in which the vehicle is positioned, auto-transformers are connected between the trolley and feeder, and the track circuit is connected to the midpoint of the said transformers. To further insure equal currents 20 flowing in the feeder and trolley circuits, these circuits are inductively interlinked by series transformers. I have found that, since the two adjacent auto-transformers at the abutting ends of two sections have equi- 25 potential values for some distance from the point at which they are connected to the track circuit, a combination of said transformer coils for a certain distance from the track can be made. The system hereinafter 30 described and claimed is of the above type and I find that by so eliminating one coil of the transformers I am able to construct the latter in the economical and efficient manner hereinafter set forth.

35 Referring to Fig. 1, a trolley conductor 1 supplies power to a railway system comprising a track 2 that is divided into a plurality of insulated sections 3 that may, at the same time, be employed as block sections for signaling purposes. A return feeder 4 paralleling the trolley conductor 1 and, preferably, being equally spaced from an intelligence-transmission circuit 5, provides means whereby the propulsion currents may 40 return to a source of power-supply, represented as a single-phase alternator 6. One terminal of the alternator 6 is connected to the trolley conductor 1, and the other terminal is connected to the feeder conductor 4, the full potential of the alternator being 45 impressed across the aforementioned conductors. Insulating joints 7 are inserted at spaced intervals in the trolley conductor 1, similar insulating joints 8 being positioned at corresponding points in the feeder conductor 4. For convenience, the insulating joints 7 and 8 may be placed at points corresponding to the position of insulating joints 9 in the track circuit 2, the latter being provided in order that sections of the track circuit may be employed as local circuits for the electric signaling system.

50 Series transformers 10, comprising primary windings 12, and secondary windings 11, are provided for each pair of insulating

joints 7 and 8 in order to inductively interlink the trolley and feeder conductors with each other. The primary windings 11 are connected in shunt to the insulating joints 7, and the secondary windings 12 are connected in shunt to the insulating joints 8. Transformer windings are provided on both sides of the insulating joints 7 and 8 in order to electrically interconnect the trolley conductor, the track circuit and 75 the feeder with one another. Between the trolley conductor 1 and the track circuit 2 are connected a winding 13 of a transformer 14 and a winding 15 of a transformer 16, the winding 15 being connected, by means 80 of a conductor 17, to mid-points 18 of impedance bonds 19. The transformer 14 also comprises a winding 20, and the transformer 16 another winding 21, the windings 20 and 21 being connected between the track circuit and the feeder conductor, as will be hereinafter explained. While the transformer 14 is connected in circuit on one side of the insulating joints 7 and 8, a similar transformer 22 is connected on the other side 90 of the insulating joints, the transformer 16 being common to both transformers 14 and 22.

From the foregoing, it will be apparent that the trolley conductor 1 is electrically 95 continuous, since the coils 11 bridge the insulating joints 7. The return feeder 4 is likewise continuous, since the coils 12 of the series transformers 10 bridge the insulating joints 8. Again, the windings 13 and 15 of the transformers 14 and 16, respectively, are interconnected between the trolley conductor 1 and the track circuit 2, and windings 20 and 21 of the transformers 14 and 16, respectively, are inserted between the track circuit 100 and the return feeder conductor 4.

When a load obtains in the track section 3, the propulsion currents flow from the track section 3 through the windings 21 and 20 to the return feeder conductor 4, the windings 15 and 13 have oppositely directed currents induced in them, as will be hereinafter explained, which currents circulate in local circuits formed through the load and the track-section 3 occupied by the load.

The signaling system, one of which is usually employed in connection with a railway system, comprises block sections which, in this instance, are the track sections 3. Each section constitutes a local circuit that is connected to a power circuit 22a by means of a track transformer 23. A signaling relay 24, of a usual form of construction, is subject to the inductive influences of a winding 25 that is connected across the rails of the track section 3 and that of a winding 26 which is energized through a second track transformer 27. The signaling relay 24 serves to control a local circuit 28 by means of which a signaling device 29 is actuated.

Inasmuch as this signaling system is old in the art, further explanation thereof is not deemed necessary.

- The intelligence-transmission circuit 5, 5 shown as a telephone circuit, is disposed in proximity to the trolley conductor 1 and the return feeder 4, and is, therefore, subject to the inductive effects arising from the flow of propulsion currents in the railway system. 10 For the satisfactory operation of the telephone circuit 5, it is essential that the inductive disturbances impressed thereupon be minimized and, to this end, my distributing system substantially reduces the flow of induced currents in the telephone circuit that 15 may arise from the flow of propulsion currents in the railway system, as will be subsequently disclosed.

In Fig. 2 is shown a simplified form of the 20 system of Fig. 1, the inductive windings of the transformers having the same designations as in Fig. 1 but being more suitably arranged to facilitate in explaining their interrelations. The signaling system has been 25 dispensed with and, as a result, the track circuit 2 is devoid of the impedance bonds 19 of Fig. 1, the track circuit, in this instance, being continuous and comprising two rails.

In this figure also is shown in what manner 30 the one winding 15 takes the place of those portions of the two auto-transformer coils 13 and 13^a, which are adjacent to the point where said coils are connected to the track circuit. It will be observed that such 35 a combination and consequent elimination of coils allows a transformer to be constructed in accordance with my invention which will occupy a relatively small space.

Assume for the purpose of illustration 40 that the telephone circuit 5 is uniformly spaced throughout its length from the trolley conductor 1 and the return feeder 4. The track circuit 2, in this instance, is presumed to be held at a potential midway 45 between that of the trolley conductor 1 and that of the feeder conductor 4 by means of the transformers 14 and 16 which are connected to the track circuit through a bond 19^a.

To illustrate the electrical conditions obtaining in the railway system of Figs. 1 and 2 at a certain instant, assume, for illustration only, that a locomotive or train 30 occupies, for an instant, a mid-position on 50 a track section intermediate the two groups of transformers. The propulsion current, which traverse the trolley and feeder circuits and the direction of flow of which is represented by the full-line arrows 31, flows 55 along the trolley conductor 1, through the winding 11 of the series transformer 10, along a section of the trolley conductor 1 and a trolley pole 32^a, to the train 30. At this point, the propulsion current divides 60 equally into two portions that flow along

the track circuit in opposite directions, since it is presumed that the track circuit 2 constitutes a uniform conductor and the train 30 occupies a mid-position upon the track section, as mentioned above. One- 70 half of the propulsion current flows through the rail bond 19^a, the winding 21 of the transformer 16, the winding 20 of the transformer 14, and the winding 12 of the series transformer 10. The other half of 75 the propulsion current flows through a rail bond 19^b, a winding 21^b of a transformer 16^b, a winding 20^b of a transformer 14^b to the return feeder 4, where the second half of the propulsion current joins the first 80 half to return to the alternator 6.

By reason of the two groups of transformers which define the railway section under discussion, and since the whole railway system is formed of sections such as 85 this, the current supplied to the load 30 and returning therefrom will be confined to the trolley conductor 1 and the return feeder 4 except in the railway section that is occupied, for the time, by the load 30. In the 90 track section 3, propulsion current will flow as long as the load 30 occupies this railway section. It is apparent, therefore, that the propulsion current flowing in the trolley section intermediate the generator 6 and 95 the point A of the system is equal in value, and flows in a direction opposite, to that of the propulsion current flowing in a corresponding portion of the return feeder 4. Therefore, the inductive effects arising 100 from the flow of the propulsion current over this portion of the system and impressed on the telephone circuit 5, are neutralized.

It becomes necessary, therefore, to neutralize the inductive effects arising from the flow of the propulsion current in the portion of the railway system or that section occupied temporarily by the load 30 and extending between the two groups of transformers shown in Figs. 1 and 2. 105

Under the conditions assumed and as mentioned above, one-half of the propulsion current flows through the winding 21 and the winding 20 of the transformers 16 and 14, respectively. Equal and oppositely directed currents are, therefore, induced in the winding 15 and in the winding 13 which are mutually inductively related to the windings 21 and 20, respectively. The direction of flow of this induced current is represented by the broken line arrows 32. A local circuit in this railway section occupied by the load 30 is consequently established over which an induced current, equal 115 to one-half of the propulsion current, flows. This local circuit comprises the winding 15, the winding 13, a section of the trolley conductor 1, the trolley pole 32^a, the train 30, a portion of the track circuit 2, and 120 125 130

the rail bond 19^a. As mentioned above, one-half of the propulsion current flows also through the windings 21^b and 20^b. In consequence thereof, a current represented by 5 the dot-and-dash arrows 33 and having a value that is equal to the second portion of the propulsion current but flowing in an opposite direction thereto, is induced in a local circuit which comprises a winding 15^b, 10 a winding 13^b, a section of the trolley conductor 1, the trolley pole 32^a, the train 30, a section of the track circuit 2 and a rail bond 19^b.

Since the induced currents flowing 15 through the windings 15 and 13 are equal and opposite to the induced currents flowing in the windings 15^b and 13^b, the said currents traversing, in opposite directions to the load 30, that portion of the trolley 20 conductor 1 included in the railway section occupied by the load 30 neutralize the separate inductive effects that are impressed upon the telephone conductor 5. Again, the inductive effects arising from the propulsion 25 current flowing along that portion of the trolley conductor 1 extending between the point A and the trolley pole 32^a are neutralized by the inductive effects arising from the portion of the return propulsion 30 current flowing along that portion of the feeder extending intermediate the two groups of transformers or the entire length of the railway section in which the load 30 is situated. As a result of the aforementioned 35 distribution of the currents, the inductive disturbances impressed upon the telephone circuit 5 are negligible, since the induced electromotive forces are substantially neutralized.

40 While the three transformers 14, 16 and 22 of Fig. 1 are shown for simplicity of illustration as having separate core members, I prefer to embody all of the transformer windings comprising the aforesaid transformers in a single unitary structure that is 45 represented in Fig. 3. The transformer 16 of Fig. 1, which comprises the coils 15 and 21, which carry current in common with the windings of both transformers 22 and 14, 50 is, therefore, centrally disposed on the core leg 34 of a magnetizable core member 35. The coils 21 and 15 have two of their terminals connected to form a common lead 36. The coil 20^a of the transformer 22, in combination with the coil 13^a, is disposed on one 55 side of the coils 21 and 15 but separated therefrom by means of magnetic shunts 37. Similarly, the coils 20 and 13 of the transformer 14 are placed on the other side of the 60 coils 21 and 15 but separated therefrom by means of magnetic shunts 37^a. The coils 20 and 20^a are connected to a common conductor 38 which, in turn, is connected to one of the remaining terminals 39 of the coil 21. 65 The coils 13^a and 13 are likewise connected

to a common conductor 40 which, in turn, is connected to a terminal 41 of the intermediate coil 15. Leads 42 and 43 extend from the coils 20^a and 20, respectively, and serve to connect the transformer to the return 70 feeder conductor 4 and across the winding 12 of the transformer 10. Leads 44 and 45 extending from the coils 13^a and 13, respectively, serve to connect the transformer to the trolley conductor 1 and across the primary winding 11 of the transformer 10. The lead 36 extends from the mid-point of the windings 15 and 21 in order to connect the transformer windings to the track circuit 2. Magnetizable shunts 37 and 37^a establish 80 paths for leakage flux, thereby magnetically segregating the three pairs of transformer coils from one another. At the same time, the three pairs of coils are disposed upon a common core member by means of which the 85 windings may be installed without requiring undue space.

In order to show the effectiveness of my transformer in preventing the flow of power currents in any one railway section other 90 than the one occupied by the load, it may be assumed that a locomotive 46 occupies a position on the railway at the right of the transformer windings 15^b and 21^b. The power currents supplied to the locomotive 46 95 traverse the primary windings 11 and 11^b of the series transformers 10 of Fig. 1, in preference to being shunted around these windings through the transformer coils 13 and 13^a, and 13^b and 13^c. If the power currents 100 tended to flow through the windings 13, 13^a, 13^b and 13^c, the return currents would not be confined to the feeder conductor but would flow in an earth return, thereby creating inductive disturbances in the telephone conductor 5. The power currents are confined, however, to the return feeder 4 since the primary windings 11 and 11^b are closely inductively linked with the secondary windings 110 respectively associated therewith and connected in series in the return feeder 4. The power currents are also substantially precluded from flowing through the transformer windings located at the ends of the separate sections because of the high impedance between the series-connected windings, such as 13^a and 15, 13 and 15, 13^b and 15^b, 13^c and 15^b, relative to the low-impedance path offered through the primary windings of the 115 series transformers, such as 10. 120

By referring to the transformer of Fig. 3, it will be noted that the windings 13 and 13^a are not closely mutually inductively related since magnetic shunts 37 are interposed therebetween. Of course, the same conditions hold with respect to the windings 13^b and 13^c. As a result, the path including windings 13 and 13^a in series relation, is a very high-impedance path and the trolley currents will not flow through this path 130

when a low-impedance path is provided, such as is offered by the primary windings 11 and 11^b which are closely mutually inductively related with the secondary coils of the 5 separate series transformers and in which equal and opposite currents obtain. As a result, the currents supplied to the locomotive 46 will be fed thereto through the trolley conductor 1 and the primary windings of 10 the spaced series transformers 10. In this manner, the electromotive forces impressed upon the telephone conductor 5 may be neutralized, since the power currents are confined to definite paths.

15 The power currents are thus confined to the trolley conductor and the return feeder only, except in those sections in which the loads are located where the power currents may traverse the track circuit. The currents 20 are prevented from flowing through the track circuit and ground, except in those sections in which the loads obtain. The currents traversing the track section of the occupied railway section, do not impress any 25 serious disturbances on the adjacent telephone circuit because the inductive effects arising therefrom are substantially neutralized, as explained above. Of course, while the description has been limited to the conditions 30 obtaining when the load occupies a central position on a railway section, the conditions obtaining when the load occupies other positions can be readily deduced since the currents will divide in proportion to the relative 35 impedances of the several paths offered for the flow of the currents in the local circuits established through the load and the transformers located at the ends of the section in which the load obtains temporarily.

40 While I have shown and described, in detail, one embodiment of my invention, it will be understood by those skilled in the art that other modifications may be made therein without departing from the spirit and scope 45 of the appended claims.

I claim as my invention:

1. A transformer comprising a common core member, a plurality of coil-groups including a middle coil-group thereon, said 50 coil-groups severally comprising an inducing and an induced winding, magnetic shunts interposed between the coil-groups, a tap extending between the inducing and induced windings of the middle coil-group, and connectors for connecting all of the inducing 55

windings together and for connecting all of the induced windings together.

2. A transformer comprising a common core member, a plurality of coil-groups including a middle coil-group thereon, said 60 coil-groups severally comprising an inducing and an induced winding, a tap extending between the inducing and induced windings of the middle coil-group, connectors for connecting all of the inducing windings together, and for connecting all the induced windings together, and magnetic shunts interposed between the several inducing windings.

3. An electric railway system comprising 70 a trolley conductor, a return feeder therefor, a track circuit, inductively related windings connected in series with the trolley conductor and the return feeder for interlinking them with each other and for dividing the system 75 into a plurality of adjacent sections, and a transformer having a plurality of inducing and induced windings connected respectively between the return feeder and the track circuit and the trolley conductor and the track 80 circuit, at least one inducing winding and one induced winding of the transformer being common to two adjacent railway sections.

4. An electric railway system comprising 85 a trolley conductor, a return feeder therefor, a track circuit, inductively related windings connected in series with the trolley conductor and the return feeder for interlinking them with each other and for dividing the 90 system into a plurality of adjacent sections, and a transformer having its inducing and induced windings connected, respectively, between the return feeder and the track circuit and the trolley conductor and the track 95 circuit, two inducing windings thereof being connected in parallel and to opposite terminals of said inductive winding that is connected in series with the feeder conductor, and a third being connected in series with 100 said parallel-connected windings for connecting them to the track circuit, the induced windings of the transformer being correspondingly arranged with respect to the trolley conductor and the track circuit and the 105 other inductive winding that is connected in series with the trolley conductor.

In testimony whereof I have hereunto subscribed my name this 26th day of Feb., 1916.

CHARLES F. SCOTT.
